CERTIFICATE OF CORRECTION

PATENT NO. : D637,116 S
APPLICATION NO. : 29/365745
DATED : May 3, 2011
INVENTOR(S) : Joachim Kettler

Page 1 of 3

It is certified that error appears in the above-identified patent and that said Letters Patent is hereby corrected as shown below:

Title page, illustrative fig. 4 should be deleted and substitute therefore the attached title page consisting of illustrative fig. 4.

In the Drawings

Fig. 4 as shown on sheet 4 of 5 should be deleted and substitute therefore the attached fig. 4 as shown on attached page 3.

Signed and Sealed this
Twenty-fifth Day of October, 2011

David J. Kappos
Director of the United States Patent and Trademark Office
